FIGURE 1 is a front perspective view of a spectrophotometer showing my new design;

FIGURE 2 is a side, cross-sectional view of a portion of the spectrophotometer shown in FIGURE 1 and taken substantially along the line 2—2 of FIGURE 1;

FIGURE 3 is a second, side, cross-sectional view taken substantially along the line 3—3 of FIGURE 1;

FIGURE 4 is a rear perspective view of the spectrophotometer;

FIGURE 5 is a side, elevational view thereof;

FIGURE 6 is a top view thereof;

FIGURE 7 is a front elevation thereof, the calibrated scale being omitted for ease of illustration; and

FIGURE 8 is a rear, elevational view thereof.

The dominant features of our design reside in the portions shown in full lines in the figures.

We claim:

The ornamental design for a laboratory spectrophotometer, substantially as shown and described.
